OSCILLATING FAN

Edward V. Sundt, 1365 Miner St., Wilmette, Ill.
Filed Feb. 14, 1958, Ser. No. 715,257
13 Claims. (Cl. 310—68)

The principal object of this invention is to provide an improved oscillating fan wherein all of the movable parts are enclosed within the motor housing, wherein a differential speed reducer is concentrically arranged with respect to the fan propelling motor shaft to provide a simple and compact construction, wherein the differential speed reducer operates to oscillate the motor housing at a desired reduced speed, and wherein oscillation of the motor housing may be started and stopped at will.

Further objects of this invention have to do with the details of construction of the oscillating fan and the cooperative relationships between the component parts thereof.

Other objects and advantages of this invention will become apparent to those skilled in the art upon reference to the accompanying specification, claims and drawings, in which:

FIG. 1 is a side elevational view of one form of the oscillating fan of this invention.

FIG. 2 is an enlarged vertical sectional view through the upper right hand portion of the oscillating fan illustrated in FIG. 1.

FIG. 3 is a vertical sectional view taken substantially along the line 3—3 of FIG. 2.

FIG. 4 is a horizontal sectional view taken substantially along the line 4—4 of FIG. 2.

FIG. 5 is a vertical sectional view taken substantially along the line 5—5 of FIG. 2.

FIG. 6 is a vertical sectional view taken substantially along the line 6—6 of FIG. 2.

FIG. 7 is an enlarged vertical sectional view similar to FIG. 2 but illustrating another form of the oscillating fan of this invention.

FIG. 8 is a vertical sectional view taken substantially along the line 8—8 of FIG. 7.

FIG. 9 is a vertical sectional view taken substantially along the line 9—9 of FIG. 7.

FIG. 10 is a vertical sectional view taken substantially along the line 10—10 of FIG. 7.

FIG. 11 is a horizontal sectional view taken substantially along the line 11—11 of FIG. 8.

FIG. 12 is a horizontal sectional view taken substantially along the line 12—12 of FIG. 8 and illustrating the control mechanism for the oscillating fan of FIG. 7.

FIG. 13 is an end elevational view of the control mechanism illustrated in FIG. 12.

FIG. 14 is a vertical sectional view taken substantially along the line 14—14 of FIG. 12.

FIG. 15 is a view similar to FIG. 12 but illustrating the parts in position for causing oscillation of the fan, FIG. 12 showing the parts in position for stopping operation of the fan.

Referring first to FIGS. 1 to 6, one form of the oscillating fan of this invention is generally designated at 10. It includes an electric motor of conventional construction having a field structure 11 and an armature 12 secured to a rotating shaft 13. The electric motor is enclosed within a motor housing formed of two parts 14 and 15 which are secured together at 16 by means of tie-bolts 17. The motor housing parts 14 and 15 are provided with bearing supports for supporting bearings 18 and 19 which rotatably mount the shaft 13. The shaft 13 projects beyond the housing part 14 and carries the usual fan and operates to propel the fan when the electric motor is energized. The motor housing parts 14 and 15 may be

2

in the form of die-castings and the bearings 18 and 19 may comprise the usual oilless bearings.

The oscillating fan also includes a stationary support 22 which may be in the form of a formed steel stand. Arranged in the top of the stand 22 are a pair of swivel members 23, which may be die-cast members, and arranged for swinging movement between the swivel members 23 is a supporting stud 24, the stud 24 being tiltably mounted in a vertical plane between the swivel members 23 by a screw 25 and nut 26. The bottom of the motor housing, at the mating joint 16, is provided with an oilless bearing member 23, the bearing member being secured in place when the motor housing parts are clamped together by the tie-bolts 17. This bearing member 23 is rotatably mounted on a cylindrical portion 27 of the supporting stud 24 and the parts are held in assembled relation by a thrust ring 29, formed of powdered iron or the like, which is press fit onto the cylindrical portion 27. In this way, the motor housing is rotatably mounted on the supporting stud 24 for substantially horizontal oscillation. At the same time, the supporting stud 24 may be swung in a vertical plane for tilting the motor housing to a desired extent. Arranged within the motor housing and formed on the supporting stud, is a reaction member 30.

A steel eccentric 32 is rigidly secured to the motor shaft 13 by means of serrations or splines 33 so as to rotate with the shaft. The eccentric 32 may ride against a washer 34 which acts as a thrust bearing for the shaft 13. Rotatably mounted on the eccentric 32 is an oscillating member or rotor 35 which may be formed of nylon or the like. The oscillating member 35 is provided with a first ring of teeth 36, there being, for purposes of illustration, 18 teeth in the ring of teeth. The oscillating member 35 is also provided with a second ring of teeth 37, there being 19 teeth in this ring of teeth.

Rotatably mounted in the housing part 15 is a gear member 39 having internal teeth 40 meshing with the first ring of teeth 36 on the oscillating member 35, the teeth 40 being 19 in number. In order to oscillate the motor housing, the gear member 39 is held against rotation and this is accomplished by means of a cam 41 carried by a shaft 42 on a knob 43. When the knob 43 is in one position, the cam 41 is free from the gear member 39 so that rotation of the gear member 39 is permitted. When, however, the knob 43 is moved to another position, the cam 41 clamps the gear member 39 against the housing part 15 to secure the gear member 39 against rotation. The second ring of teeth 37 on the oscillating member 35 meshes with teeth 45 on a second gear member 46 which is rotatably mounted on the shaft 13, the teeth 45 being 20 in number. The second gear member 46 is provided with an eccentric 47 which is arranged between a pair of fingers 49 which form a yoke on the reaction member 30.

Electrical energy is supplied to the electric motor through suitable wires under the control of an electric switch 51 arranged within the stationary support 22 and operated by a lever 52. When the switch 51 is turned on, the electric motor is operated to propel the fan 20 and when it is turned off, the electric motor is stopped. The eccentric 32 driven by the shaft 13 and the oscillating member 35, first gear member 39 and second gear member 46 form a differential speed reducer which is concentrically arranged about the shaft 13, this differential speed reducer operating, when the first gear member 39 is secured against rotation, to rotate the eccentric 47 at a reduced speed. The eccentric 47 cooperates with the stationary yoke formed by the fingers 49 to cause the motor housing to oscillate substantially horizontally at reduced speeds.

The formula for determining the speed reduction ratio

between the second gear member 46 and the eccentric 32 and hence the shaft 13 may be expressed as follows:

$$\text{Ratio} = \frac{1 - \frac{ac}{bd}}{1}$$

where a , b , c and d , respectively are the numbers of teeth on the first gear member 39, in the first ring 36 of teeth on the oscillating member 35, in the second ring 37 of teeth on the oscillating member 35 and on the second gear member 46. By substituting the appropriate values, as expressed above, the speed reduction ratio becomes

$$\text{Ratio} = \frac{1 - \left(\frac{19 \times 19}{18 \times 20} \right)}{1} = \frac{76}{1}$$

Various speed reduction ratios may be obtained by appropriately selecting desired gear ratios between the first gear member 39, the oscillating member 35 and the second gear member 46. Assuming that the motor shaft 13 is rotated at a speed of substantially 1750 r.p.m., and with this speed reduction ratio of 360 to 1, the eccentric 47 is rotated at a speed of substantially 5 r.p.m. so that the fan housing is oscillated substantially 5 times per minute. Any time that it is desired to stop oscillation of the motor housing while the electric motor is oscillating, the knob 43 may be manipulated to release the first gear member 39 and when this is done, the first gear member 39 is allowed to rotate freely, thus preventing rotation of the eccentric 47 by the second gear member 46.

The first gear member 39 may be formed of steel or the like and preferably the second gear member 46 and eccentric 47 are formed of powdered iron impregnated with a suitable lubricant for lubricating the running surfaces including those between the shaft 13, the eccentric 47 and the yoke fingers 49. The yoke member or reaction member 30 which is an extension of the supporting stud is preferably a die-cast part. In the form of the invention illustrated in FIGS. 1 to 6, it is possible to obtain easily, an angle of oscillation of substantially 45 degrees, this angle being limited by the relationships between the eccentric 47 and the yoke fingers 49.

Another form of the oscillating fan of this invention is illustrated in FIGS. 7 to 15 and is generally designated at 55 therein. This form of the invention is very much like the form described above and like reference characters have been utilized for like parts. This form of the invention differs from the other form of the invention in two essential respects, one, provision is made for providing an angle of oscillation of the motor housing up to 90 degrees, and two, a single actuator is utilized for starting and stopping operation of the electric motor and starting and stopping oscillation of the motor housing. The oscillating fan of FIGS. 7 to 13 utilizes substantially the same motor construction, stationary support and differential speed reducer, and as expressed above, like reference characters have been utilized for like parts.

However, in the oscillating fan 55 of FIGS. 7 to 15 the reaction member 30 does not itself carry the yoke. Instead, the reaction member 30 is provided with a plurality of beveled teeth 60 which are concentric with the axis of the supporting stud 24. A yoke 62 has beveled teeth 61 which mesh with the teeth 60 on the reaction member 30 and the yoke 62 is pivoted to the field structure of the electric motor by a spring sleeve 64. The yoke 62 is provided with a central opening 63 which receives the eccentric 47 rotated by the second gear member 46. Thus, as the eccentric 47 is rotated at reduced speeds by the differential speed reducer, the pivoted yoke 62 is oscillated and reacts against the stationary reaction member 30 through the beveled gear teeth 60 and 61. The pivoted yoke 62, therefore, operates as a multiplying member for

providing substantially 90 degrees oscillation to the motor housing. The upper end of the pivoted yoke 62 is provided with surfaces 65 which cooperate with projections on the cam member 67 of the control mechanism for purposes hereinafter to be described.

The cam member 67 is arranged within the motor housing adjacent the top thereof and it is secured by a rivet 68 to a shank 69 on a knob 70. The cam member 67 is provided with a cam surface 71 which is adapted to be moved from a position illustrated in FIG. 10 where it is free from the first gear member 39 to a position as illustrated in FIG. 15 where it engages the first gear member 39 to secure the same against rotation. A terminal block 73 is secured to the motor housing part 15 adjacent the cam member 67 by means of a spacer 74 and a rivet 75. This terminal block carries a pair of terminals 76 and 77 provided with contacts 78 and 79. The terminals 76 and 77 are connected in series with the electric motor so that when the contacts 78 and 79 thereof are bridged, the motor is operated and so that when the contacts 78 and 79 are disconnected, operation of the electric motor is stopped. The contacts 78 and 79 are selectively bridged by a contact strip 81 carried by the cam member 67, the contact strip being secured thereto by embedding the ends 82 thereof in the cam member 67.

When the parts are in the position illustrated in FIG. 12 the contact strip 81 does not bridge the contacts 78 and 79 and, as a result, the electric motor is deenergized. Also, the cam surface 71 is displaced from the first gear member 39 so that the first gear member 39 is not secured against rotation. When the cam member 67 is moved to a position intermediate the positions illustrated in FIGS. 12 and 15, the contact strip 81 bridges the contacts 78 and 79 to cause operation of the electric motor and propelling of the fan. However, in this intermediate position the cam surface 71 does not engage the first gear member 39 so that the first gear member is not secured against rotation. Accordingly, the differential speed reducer is not operative to cause oscillation of the motor housing even though the fan is propelled. In this intermediate position the fan may be placed in any desired position and run without oscillation.

When the cam member 67 is moved to the position illustrated in FIG. 15, the contacts 78 and 79 remain bridged by the contact strip 81 so that the electric motor continues in operation to propel the fan. In this position, the cam surface 71 engages the first gear member 39 to cause the differential speed reducer to operate to oscillate substantially horizontally the motor housing through substantially 90 degrees. By rotating the cam member 67 from the position illustrated in FIG. 15 to the position illustrated in FIG. 12 oscillation of the motor housing is interrupted and operation of the electric motor is stopped.

If oscillation of the motor housing is stopped when it is at one end or the other end of its oscillating movement, as illustrated in dotted lines in FIG. 8, the eccentric 47 would be on dead center with respect to the yoke 62 so that it would be substantially impossible to manually position the motor housing even though the first gear member 39 is released for rotation. To prevent this, the cam member 67 is provided with a pair of projections 84 and 85 which cooperate with the top surface 65 of the pivoted yoke 62. When the pivoted yoke 62 is in either extreme position the top surface 65 of the yoke comes in alignment with one or the other projections 84 and 85 to prevent movement of the cam member 67 out of the position illustrated in FIG. 15. Under these conditions, it is impossible to stop operation of the motor. Movement of the cam member 67 and stopping of the operation of the motor is permitted only when the pivoted yoke 62 is moved from its extreme positions. This eliminates stopping on dead center so that the fan housing may be manually manipulated to desired positions when oscillation of the motor housing is not desired.

While for purposes of illustration, two forms of this invention have been disclosed, other forms thereof may become apparent to those skilled in the art upon reference to this disclosure and, therefore, this invention is to be limited only by the scope of the appended claims.

I claim as my invention:

1. In an oscillating fan, a motor housing, an electric motor in the motor housing and having a substantially horizontally arranged shaft rotated thereby for propelling the fan, a stationary support extending into the motor housing, means for rotatably mounting the motor housing on the support for substantially horizontal oscillation thereof, a differential speed reducer in the motor housing concentric with the motor shaft and driven thereby, a stationary reaction member in the motor housing and secured to the support within the motor housing above the motor housing mounting means, and means in the motor housing connecting the differential speed reducer to the reaction member for causing the motor housing to oscillate substantially horizontally at a reduced speed as the electric motor is operated, said last mentioned means including an eccentric driven by the differential speed reducer and a yoke encompassing said eccentric and connected with the reaction member.

2. In an oscillating fan, a motor housing, an electric motor in the motor housing and having a substantially horizontally arranged shaft rotated thereby for propelling the fan, a stationary support extending into the motor housing, means for rotatably mounting the motor housing on the support for substantially horizontal oscillation thereof, a differential speed reducer in the motor housing concentric with the motor shaft and driven thereby, a stationary reaction member in the motor housing and secured to the support within the motor housing above the motor housing mounting means, and means in the motor housing connecting the differential speed reducer to the reaction member for causing the motor housing to oscillate substantially horizontally at a reduced speed as the electric motor is operated, said last mentioned means including an eccentric driven by the differential speed reducer and a yoke formed on the reaction member and encompassing said eccentric.

3. In an oscillating fan, a motor housing, an electric motor in the motor housing and having a substantially horizontally arranged shaft rotated thereby for propelling the fan, a stationary support extending into the motor housing, means for rotatably mounting the motor housing on the support for substantially horizontal oscillation thereof, a differential speed reducer in the motor housing concentric with the motor shaft and driven thereby, a stationary reaction member in the motor housing and secured to the support within the motor housing above the motor housing mounting means, and means in the motor housing connecting the differential speed reducer to the reaction member for causing the motor housing to oscillate substantially horizontally at a reduced speed as the electric motor is operated, said last mentioned means including an eccentric driven by the differential speed reducer, a pivoted yoke encompassing the eccentric and oscillated thereby, and gear teeth connections between the pivoted yoke and the reaction member.

4. In an oscillating fan, a motor housing, an electric motor in the motor housing and having a substantially horizontally arranged shaft for propelling the fan, a stationary support extending into the motor housing, means for rotatably mounting the motor housing on the support for substantially horizontal oscillation, a differential speed reducer in the motor housing concentrically arranged about the shaft and including an eccentric rotated by the shaft, an oscillating member rotatably mounted on the eccentric and including a pair of rings of teeth, a first gear meshing with one ring of teeth on the oscillating member for controlling the oscillating member, means for securing the first gear member against rotation and a second gear meshing with the other ring of teeth on

the oscillating member and rotated thereby at reduced speed when the first gear member is secured against rotation, a stationary reaction member within the motor housing and secured to the support within the motor housing above the motor housing mounting means, and means within the motor housing connecting the second gear to the reaction member for causing the motor to oscillate substantially horizontally at a reduced speed as the electric motor is operated.

10 5. In an oscillating fan, a motor housing, an electric motor in the motor housing and having a substantially horizontally arranged shaft for propelling the fan, a stationary support extending into the motor housing, means for rotatably mounting the motor housing on the support for substantially horizontal oscillation, a differential speed reducer in the motor housing concentrically arranged about the shaft and including an eccentric rotated by the shaft, an oscillating member rotatably mounted on the eccentric and including a pair of rings of teeth, a first gear meshing with one ring of teeth on the oscillating member for controlling the oscillating member, means for securing the first gear member against rotation, and a second gear meshing with the other ring of teeth on the oscillating member and rotated thereby at reduced speed when the first gear member is secured against rotation, a stationary reaction member within the motor housing and secured to the support within the motor housing above the motor housing mounting means, and means within the motor housing connecting the second gear to the reaction member for causing the motor to oscillate substantially horizontally at a reduced speed as the electric motor is operated, said last mentioned means including an eccentric driven by the second gear and a yoke encompassing said eccentric and connected 20 25 30 25 with the reaction member.

35 with the reaction member.

6. In an oscillating fan, a motor housing, an electric motor in the motor housing and having a substantially horizontally arranged shaft for propelling the fan, a stationary support extending into the motor housing, means
40 for rotatably mounting the motor housing on the support for substantially horizontal oscillation, a differential speed reducer in the motor housing concentrically arranged about the shaft and including an eccentric rotated by the shaft, an oscillating member rotatably mounted
45 on the eccentric and including a pair of rings of teeth, a first gear meshing with one ring of teeth on the oscillating member for controlling the oscillating member, means for securing the first gear member against rotation, and a second gear meshing with the other ring of
50 teeth on the oscillating member and rotated thereby at reduced speed when the first gear member is secured against rotation, a stationary reaction member within the motor housing and secured to the support within the motor housing above the motor housing mounting means,
55 and means within the motor housing connecting the second gear to the reaction member for causing the motor to oscillate substantially horizontally at a reduced speed as the electric motor is operated, said last mentioned means including an eccentric driven by the second gear
60 and a yoke formed on the reaction member and encompassing said eccentric.

7. In an oscillating fan, a motor housing, and electric motor in the motor housing and having a substantially horizontally arranged shaft for propelling the fan, a stationary support, means for rotatably mounting the motor housing on the support for substantially horizontal oscillation, a differential speed reducer in the motor housing concentrically arranged about the shaft and including an eccentric rotated by the shaft, an oscillating member 65 rotatably mounted on the eccentric and including a pair of rings of teeth, a first gear meshing with one ring of teeth on the oscillating member for controlling the oscillating member, means for securing the first gear member against rotation, and a second gear meshing with 70 the other ring of teeth on the oscillating member and 75

rotated thereby at reduced speed when the first gear member is secured against rotation, a stationary reaction member within the motor housing and secured to the support within the motor housing above the motor housing mounting means, and means within the motor housing connecting the second gear to the reaction member for causing the motor to oscillate substantially horizontally at a reduced speed as the electric motor is operated, said last mentioned means including an eccentric driven by the second gear, a pivoted yoke encompassing the eccentric and oscillated thereby, and gear teeth connections between the pivoted yoke and the reaction member.

8. In an oscillating fan, a motor housing, an electric motor in the motor housing and having a substantially horizontally arranged shaft rotated thereby for propelling the fan, a manually operated switch carried by the motor housing and connected to the electric motor for controlling the operation of the same, a stationary support, means for rotatably mounting the motor housing on the support for substantially horizontal oscillation thereof, a differential speed reducer in the motor housing concentric with the motor shaft and driven thereby, a control device for selectively rendering the differential speed reducer operative and inoperative, means interconnecting the manually operated switch and the control device for rendering the differential speed reducer operative only when the electric motor is operating, a stationary reaction member in the motor housing and secured to the support, and means in the motor housing connecting the differential speed reducer to the reaction member for causing the motor housing to oscillate substantially horizontally at a reduced speed when the speed reducer is rendered operative.

9. In an oscillating fan, an electric motor having a substantially horizontally arranged shaft for propelling the fan, a manually operated switch connected to the electric motor for controlling the operation of the same, a stationary support, means for rotatably mounting the motor on the support for substantially horizontal oscillation, a differential speed reducer concentrically arranged about the shaft and including an eccentric rotated by the shaft, an oscillating member rotatably mounted on the eccentric and including a pair of rings of teeth, a first gear meshing with one ring of teeth on the oscillating member for controlling the oscillating member, a control device for selectively securing the first gear against rotation, means interconnecting the manually operated switch and the control device for securing the first gear against rotation only when the electric motor is operating, a second gear meshing with the other ring of teeth on the oscillating member and rotated thereby at reduced speed when the first gear member is secured against rotation, a reaction member secured to the support, and means connecting the second gear to the reaction member for causing the motor to oscillate substantially horizontally at a reduced speed when the first gear is secured against rotation.

10. In an oscillating fan, an electric motor having a substantially horizontally arranged shaft for propelling the fan, a manually operated switch connected to the electric motor for controlling the operation of the same, a stationary support, means for rotatably mounting the motor on the support for substantially horizontal oscillation, a differential speed reducer concentrically arranged about the shaft and including an eccentric rotated by the shaft, an oscillating member rotatably mounted on the eccentric and including a pair of rings of teeth, a first gear meshing with one ring of teeth on the oscillating member for controlling the oscillating member, a control device for selectively securing the first gear against rotation, means interconnecting the manually operated switch and the control device for securing the first gear against rotation only when the electric motor is operating, a second gear meshing with the other ring of teeth on the oscillating member and rotated thereby at reduced speed

when the first gear member is secured against rotation, an eccentric driven by the second gear, a yoke associated with the stationary support and encompassing the eccentric for causing the motor to oscillate substantially horizontally at a reduced speed when the first gear is secured against rotation, and means associated with the manually operated switch and the yoke to prevent manual operation of the switch to stop operation of the motor when the motor is in an end position of its substantially horizontal oscillation.

11. In an oscillating fan, a motor housing, an electric motor in the motor housing and having a substantially horizontally arranged shaft rotated thereby for propelling the fan, a manually operated switch carried by the motor housing and connected to the electric motor for controlling the operation of the same, a stationary support, means for rotatably mounting the motor housing on the support for substantially horizontal oscillation thereof, a differential speed reducer in the motor housing concentric with the motor shaft and driven thereby, a control device for selectively rendering the differential speed reducer operative and inoperative, means interconnecting the manually operated switch and the control device for rendering the differential speed reducer operative only when the electric motor is operating, a stationary reaction member in the motor housing and secured to the support, and means in the motor housing connecting the differential speed reducer to the reaction member for causing the motor housing to oscillate substantially horizontally at a reduced speed when the speed reducer is rendered operative, and means associated with the manually operated switch and the last mentioned means to prevent manual operation of the switch to stop operation of the motor when the motor housing is in an end position of its substantially horizontal oscillation.

12. In an oscillating fan, an electric motor having a substantially horizontally arranged shaft for propelling the fan, a manually operated switch connected to the electric motor for controlling the operation of the same, a stationary support, means for rotatably mounting the motor on the support for substantially horizontal oscillation, a differential speed reducer concentrically arranged about the shaft and including an eccentric rotated by the shaft, an oscillating member rotatably mounted on the eccentric and including a pair of rings of teeth, a first gear meshing with one ring of teeth on the oscillating member for controlling the oscillating member, a control device for selectively securing the first gear against rotation, means interconnecting the manually operated switch and the control device for securing the first gear against rotation only when the electric motor is operating, a second gear meshing with the other ring of teeth on the oscillating member and rotated thereby at reduced speed when the first gear member is secured against rotation, a reaction member secured to the support, and means connecting the second gear to the reaction member for causing the motor to oscillate substantially horizontally at a reduced speed when the first gear is secured against rotation, and means associated with the manually operated switch and the last mentioned means to prevent manual operation of the switch to stop operation of the motor when the motor is in an end position of its substantially horizontal oscillation.

13. In an oscillating fan, a motor housing, an electric motor in the motor housing and having a field structure carried by the housing, an armature in the field structure, and a substantially horizontal shaft carrying the armature and rotated thereby for propelling the fan, a pair of bearings in the motor housing for rotatably mounting the shaft, a manually operated switch carried by the motor housing and connected to the electric motor for controlling the operation of the same, a differential speed reducer in the motor housing concentric with and supported by the motor shaft and driven thereby, a stationary support, means for rotatably mounting the motor housing on the

support for substantially horizontal oscillating thereof, a stationary reaction member in the motor housing and secured to the support, and means in the motor housing connecting the differential speed reducer to the reaction member for causing the motor housing to oscillate substantially at a reduced speed as the electric motor is operated, and means associated with the manually operated switch and the last mentioned means to prevent manual operation of the switch to stop operation of the motor when the motor housing is in an end position of its substantially horizontal oscillation.
